UNITED STATES PATENT OFFICE

149,602

DESIGN FOR A SPECTACLE HOLDER ATTACHMENT FOR TELEPHONES

Grace H. Yost, St. Louis County, Mo.

Application October 26, 1946, Serial No. 134,275

Term of patent 14 years

(Cl. D26—14)

To all whom it may concern:

Be it known that I, Grace H. Yost, a citizen of the United States and a resident of the county of St. Louis and State of Missouri, have invented a new, original, and ornamental Design for a Spectacle Holder Attachment for Telephones, of which the following is a specification, reference being had to the accompanying drawing, forming part thereof.

Fig. 1 is a perspective view of a spectacle holder attachment for telephones showing my new design;

Fig. 2 is a top plan view thereof;

Fig. 3 is a front elevational view thereof; and
Fig. 4 is a side elevational view.

The dotted line representation is for illustrative purposes only.

I claim:

The ornamental design for a spectacle holder attachment for telephones, as shown and described.

GRACE H. YOST.
